(57) **CLAIM**

I claim the ornamental design for a pet collar with interchangeable elements, as shown and described.

DESCRIPTION

FIG. 1 is a perspective view of a pet collar with interchangeable elements, showing my new design;

FIG. 2 is an exploded top perspective view thereof;

FIG. 3 is an exploded bottom perspective view thereof;

FIG. 4 is a bottom plan view thereof;

FIG. 5 is a top plan view thereof;

FIG. 6 is a left-side elevational view thereof;

FIG. 7 is a right-side elevational view thereof;

FIG. 8 is a rear elevational view thereof; and,

FIG. 9 is a front elevational view thereof.

The broken lines showing a dog in FIG. 1 depict environmental matter and form no part of the claimed design.

1 Claim, 3 Drawing Sheets
